AUTOMOBILE TRASH RECEPTACLE

Victor A. Hopp, Ringwood, Ill.

Application May 28, 1958, Serial No. 738,418

5 Claims. (Cl. 206—19.5)

My invention relates to a trash receptacle for automobiles and more specifically to a combination of a disposable container and a support therefor easily attached in a convenient location inside an automobile into which litter may be deposited and which may be bodily removed and disposed of when full.

Trash such as Kleenex, candy wrappers, scrap paper, etc., has presented a problem in automobiles in that no one enjoys throwing such matter out of the car to litter the roadsides and yet no satisfactory way of accommodating this material is provided in the automobile.

My invention is directed to a receptacle or more properly to a container and a support therefor, which is to accommodate trash of this character. The support is exceedingly inexpensive and easily attachable to the inside of an automobile in a location which is convenient and within reach of the driver or front seat passengers and yet which is out of the way so as not to impair the comfort of persons riding in the automobile. The container of my invention is inexpensive to the point of being disposable, is easily attached to the support and, when full, may be torn from the support and disposed of without the need for handling the trash contained therein directly. My invention provides that the container thereof is closed except when trash is actually being placed therein.

Other objects and advantages of my invention will be apparent from the following description and drawings of which:

Fig. 1 is a side elevation of a receptacle embodying my invention shown attached to the dashboard of an automobile;

Fig. 2 is a top plan view of the receptacle embodying my invention;

Fig. 3 is an enlarged end elevation of one of the frame joints of my invention taken substantially from line 3—3 of Fig. 1 looking in the direction of the arrows;

Fig. 4 is an enlarged side elevation of the joint of Fig. 3; and

Fig. 5 is a perspective of the container portion of my invention prior to attachment to the support portion thereof.

The illustrated receptacle embodying my invention consists essentially of a support 10 and a container 12. The support includes a pair of arms 14 formed of spring steel strips. About midway of their length the strips are twisted through 90° at 16 so that the strips at the inner part 18 of the arms are generally horizontal and at the outer part are generally vertical. The inner part of each arm is recurved upwardly on itself to define a relatively large loop 22. The extreme free end of the inner part of the arm has corrugations 24 thereon, and the curvature defining the loop 22 brings the corrugated portion 24 in close proximity to the more central flat portion of the inner part to constitute a spring clip indicated generally by 25.

The support portion also includes a three-sided rectangular inner frame 26 formed of relatively stiff and

2

strong wire and having a back 28 and sides 30 extending downwardly from the ends of the back. The sides 30 terminate in eyes 32. The support also comprises a second, outer frame 34 which likewise has a back 36 and sides 38 extending downwardly from the ends of the back and terminating in similar eyes 40. The two frames 26 and 34 are substantially identical in size.

The frames are secured together for pivotal movement with respect to each other by placing the frames in side by side relation, springing the frames sufficiently to bring adjacent eyes into alignment and passing grommets 42 through the two pair of eyes to secure the frames together, side-to-side and back-to-back.

A small diameter coil spring 44 having ends of appreciable length is inserted into each of the grommets.

Hooks 46 are formed on the ends of the springs. The springs are pre-tensioned and the hook ends are then latched about the frame sides 30, 38 to urge the two frames together.

20 The free ends 48 of the outer parts 20 of the spring steel arms 14 are stamped about the upper ends of the sides 30 of the inner frame 26 to secure the arms to that frame.

25 The back 36 of the outer frame 34 may include a central portion thereof offset horizontally to the front to define a handle 50.

The illustrated container portion 12 of my invention is essentially a modified form of a conventional paper bag. The bottom and sides 58 of the bag will be formed in the usual fashion. The bag is, however, relatively shallow so that the vertical height thereof is about equal to the width. Additionally, the longitudinal sides of the bag are extended upwardly above the ends of the bag to define flaps 60. The flaps are gummed as at 62 along their top edge on the outside surfaces thereof. Below the line of gumming, the flaps are perforated across as at 64. One of the flaps has a narrow rectangular aperture 66 therein in the line of perforation 64 and centrally of the flap. The aperture 66 is proportioned to admit the handle 38 therethrough.

20 The use of the receptacle will be evident from the foregoing description.

A representative dashboard 68 of an automobile is shown in transverse section in Fig. 1. A portion 70 thereof slopes downwardly and away from the passengers in the front seat or toward the front of the car. At the end of this slope the dashboard extends horizontally as at 72 toward the front of the car and terminates in an upturned lip 74 underneath the dashboard. I contemplate that the receptacle of my invention be secured to the underside of the dashboard in approximately the center thereof so as to be accessible both to the driver and passenger and at the same time not be bumped by the knees of either. The support 12 is secured to the dashboard by manually springing open the spring clips 25 and hooking the clips over the inner edge of lip 74 of the dashboard. The support then extends rearward or outward, and the support should be so positioned on the dashboard that the back 28 of frame 26 lies at about the line of transition between the horizontal dashboard portion 72 and the sloping portion 70 or even farther forward under the horizontal part of the dashboard. In this position, the receptacle of my invention is accessible for the deposit of trash and yet is out of the way and substantially concealed from view.

70 The corrugations of the clips 25 bear firmly against the portion 72 of the dashboard and anchor it firmly in place. The large loop 22 of the clip will accommodate a wide variety of lips 74.

The bag or container is attached to the frame by first moistening the gummed flap edges 62 and then passing the flaps up between the horizontal frame backs 28 and 36.

The gummed surfaces lie back to back in the process of installing the bag so that there is no danger of mutual adherence. The flaps are carried upward between backs 28 and 36 until the aperture 66 may be placed over the handle 50. The bag is withdrawn slightly at this point so as to bring the aperture 66 snugly up against back 36 and cause handle 50 to protrude therefrom. The flaps may then be anchored into position and the frames separated so that the hand can be inserted into the container to press the gummed flap edges back on the lower unguammed portions of the flaps so as to wrap the flaps around the backs 28 and 36 and so secure the container thereto. By this mode of placement, the lines of perforations 64 in the flaps lie against the upper surfaces of the frame backs 28 and 36.

In use, when trash is to be deposited, the driver or passenger of the automobile will simply pull upon the handle to spread open the bag and place the waste in the container. When the handle is released, the two frames close together, so closing the container.

When the container becomes full, the flaps may be seized and simply torn off the backs 28 and 36 of the frames, the paper loops enclosing the frame backs tearing and opening on the lines of perforation 64. The container may then be bodily dropped in a filling station receptacle.

It is reasonable to expect that changing containers may be provided as a gratuitous and routine filling station service just as checking oil and water and cleaning the windshields.

It will be evident from the foregoing description that I have provided a trash receptacle for automobiles which is exceedingly inexpensive to manufacture and readily installed, which is readily accessible for purposes of trash disposal and yet which is out of the way so as not to impair a passenger's comfort and inconspicuously located so as not to offend the eye. As a part of the receptacle, it will be appreciated that I have provided a container designed for disposability, which may be easily attached to and even more easily detached from its supporting structure. My structure likewise provides that the container be closed at all times except when trash is being deposited therein.

It will likewise be evident that although I have described an embodiment only of my invention, many alternatives both as to structure and materials may be employed in the practice of my invention. For instance, the container portion of my invention need not necessarily be formed of paper. Other materials may be employed such as an inexpensive plastic. Any alternative container, however, should have a pre-determined line of failure such as the lines of perforations of the illustrated paper bag so that the container may be torn from the frame without imposing undue strain on the frame. I, therefore, desire that my invention be regarded as being limited only as set forth in the following claims.

I claim:

1. An automobile trash receiver comprising a pair of similarly proportioned, three-sided rectangular frames, each of said frames having a back and sides extending from said back, pivotally connected together at the free ends of the sides thereof for movement against and away from each other, spring means urging said frames against each other, a paper bag having upstanding flaps on opposite sides thereof secured about the backs of said frames to support said bag between the sides of said frames, said flaps being longitudinally perforated in that portion thereof encircling the backs of said frames, and means secured to one of said frames for supporting said frames from the underside of the dashboard of an automobile generally vertically with the backs thereof uppermost.

2. An automobile trash receiver comprising a pair of similarly proportioned, three-sided, rectangular frames,

each of said frames having a back and sides extending from said back, pivotally connected together at the free ends of the sides thereof for movement against and away from each other, spring means urging said frames against each other, a container having portions thereof secured about the backs of said frames to support said container between the sides of said frames, a pair of spring steel strip arms twisted through a right angle between the ends thereof, one end of said arms being secured flat against the sides of one of said frames adjacent the back of said frame to extend from the plane of said frame generally perpendicularly and the other end of said arms being recurved on itself to define clips engageable over the underside of the dashboard of an automobile to hold said arms against the underside of said dash board and support said frames generally vertically with the backs thereof uppermost.

3. An automobile trash receiver comprising a pair of similarly proportioned, three-sided, rectangular frames, each of said frames having a back and sides extending from said back, pivotally connected together at the free ends of the sides thereof for movement against and away from each other, spring means urging said frames against each other, a container having portions thereof secured about the backs of said frames to support said container between the sides of said frames, arms secured to one of said frames and extending from said plane generally perpendicularly to the plane thereof for supporting said frames from the underside of the dashboard of an automobile generally vertically with the backs thereof uppermost, said other frame having a portion of the back thereof offset out of the plane thereof away from said one frame.

4. An automobile trash receiver comprising a pair of similarly proportioned, three-sided, rectangular frames, each of said frames having a back and sides extending from said back, pivotally connected together at the free ends of the sides thereof for movement against and away from each other, spring means urging said frames against each other, a disposable upstanding bag having upstanding flaps on opposite sides thereof secured about the backs of said frames to support said container between the sides of said frames, said flaps having a longitudinal line of failure in that portion thereof encircling the backs of said frames to facilitate tearing said bag from said frames, and means secured to one of said frames for supporting said frames from the underside of the dashboard of an automobile generally vertically with the backs thereof uppermost.

5. An automobile trash receiver comprising a pair of similarly proportioned, three-sided, rectangular frames, each of said frames having a back and sides extending from said back, pivotally connected together at the free ends of the sides thereof for movement against and away from each other, spring means urging said frames against each other, a disposable upstanding bag having upstanding flaps on opposite sides thereof secured about the backs of said frames to support said container between the sides of said frames, and means secured to one of said frames for supporting said frames from the underside of the dashboard of an automobile generally vertically with the backs thereof uppermost, the back of the other frame having a portion thereof offset from the plane of said frame away from said one frame and the flap encircling the back of said other frame having aperture therein positioned to permit said offset portion to extend therethrough.
